UNITED STATES PATENT OFFICE

JAMES A. MALCOLM, OF SHERADEN, AND THOMAS W. WOOTTON, OF BELLEVUE, PENNSYLVANIA; SAID WOOTTON ASSIGNOR TO SAID MALCOLM

APPARATUS FOR REPRODUCING CONTOURS OF SURFACES

Application filed January 9, 1930. Serial No. 419,569.

This invention relates to apparatus for reproducing contours of surfaces, and more particularly to apparatus for recording the undulations of facial surfaces.

5 An object of the present invention is to provide an apparatus for conveniently obtaining accurate profiles as well as measurements of the human face.

In the construction of plates in dentistry, it 10 is often desirable to have a profile of a patient's face as it was originally, or before the removal of any teeth, so that the profile may be restored to its former state or else improved upon. Heretofore various means 15 have been employed for obtaining profiles but none have proved entirely satisfactory. For example, wire has been shaped on the face to correspond with the profile but in transferring the wire from the face to a piece of 20 paper for tracing, the wire is not likely to retain its shape, and upon drawing a pencil along the side thereof, the outline is not likely to be an accurate reproduction.

The present invention comprises an apparatus of simple construction which may be readily attached to the head of a person, as is illustrated in the accompanying drawings, in which

25 Figure 1 is a side elevational view of the apparatus shown in position for taking the profile of the human face,

Fig. 2 is an elevational end view of the device,

30 Fig. 3 is an enlarged cross-sectional view 35 taken on line III—III of Fig. 2, and shows a plan view partly in cross-section of portions of the apparatus in the direction of the arrows.

Fig. 3a and 3b are modifications of a portion of the apparatus, to be described later,

40 Fig. 4 is a perspective view of the device applied in a manner set forth below,

Fig. 5 is a cross-sectional view of Fig. 3 45 taken on line V—V,

Fig. 6 is a cross-sectional view of Fig. 3 taken on line VI—VI, and

Fig. 7 is a detailed view of a portion of the apparatus.

The apparatus comprises a rod 1 which is 50 adapted to be placed adjacent the human face

or other object; a carrier member designated generally by the letter A and which is mounted on the rod 1 in such a manner that it may be moved along the said rod and also toward and away from the face or object; a means 3 which extends from the carrier member A and the end of which is adapted to be drawn across the skin or other surface; and a pencil or other marking means 4 which is also mounted on the carrier member A and which is adapted to come into contact with a card 5 which is mounted on a target 6.

The carrier member A comprises rods 7 and 8 (Fig. 3) which slide through two drilled holes in a block 9. The block 9 is provided with a third hole and a bushing 10 through which the rod 1 passes so that the block is free to move the carrier member from one end of the rod 1 to the other. The ends of the rods 7 and 8 are connected by means of cross pieces 11 and 12.

A tube 13, which serves to hold the marking means in place, is pivotally connected at its center to the cross piece 12 so that it may be turned in any direction in a plane at right angles to the bars 7 and 8. Suitable means may be provided whereby the tube may be held in any given position. The marking means 4 projects from one end of the tube 13 and its point is kept in an outward position by a spring 15.

The means 3 is fastened to the cross piece 11 by inserting one end into a hole in the latter and holding it in place by means of a screw 14. The means 3 may be provided with a roller 16 at its free end, or it may be pointed as shown in Fig. 3a, or provided with a knob 17 as shown in Fig. 3b.

A handle 18 may be attached at any convenient place, such as the center of the cross piece 19.

The tablet 6 is mounted on a rod 20 by means of a supporting member 21 which is attached to one side of the tablet. A rod 22 extends from the supporting member 21 to a sleeve 23. The sleeve is held in position on the rod 20 by means of a set screw 24. As shown in Fig. 2, the tablet 6 may be placed parallel with or at right angles to the rod 20. This is accomplished by attaching the sup-

porting member 21 to a sleeve 25 (Figs. 4 and 7) through which the rod 22 passes. The tablet 6 may be turned about the rod 22 and may be held in position on this rod by a set 5 screw 26.

For the purpose of attaching the apparatus to the head of a person, the plate member 28 extends from the upper ends of rods 1 and 20 and is attached to a head gear designated 10 generally by numeral 29. Extending from the lower ends of the rods 1 and 20, is a strap member 30 provided with a slot 31. An extension 32 also provided with a slot 33 is fastened to the slotted end of the member 30 15 by means of a thumb nut 34. The extension 32 is provided with a means 35 which may rest comfortably against the person's neck, or under the jaws as shown in dotted lines in Fig. 1. By means of the thumb nuts 34 20 and 36, the apparatus may be set in the desired position with respect to the face.

In the operation of the apparatus described for obtaining the vertical profile of the face, for instance, the tablet 6 may be held in vertical position and the pencil 4 is placed in contact with a card 5 which may be fastened to the tablet by bent over portions 27 at the edges thereof. By grasping the handle 18 the means 3 is drawn across the surface of 30 which an outline is to be obtained. The pencil will mark on the card the exact path taken by the outer end of the means 3. In reproducing profiles of the face, the means 3 should preferably be curved so that only the outer 35 end thereof may be brought into contact with the skin surface under the person's nose and chin.

It is sometimes necessary, as for instance in obtaining a record to indicate irregularities in the horizontal profile of the human face, to place the tablet 6 in a horizontal position as shown in Fig. 4 and in dotted lines in Fig. 2. In this case the tablet 6 is turned about the rod 22 and may be raised or 45 lowered on the rod 20 depending upon the level at which the record is to be taken. The tube 13 is placed in a vertical position so that the pencil 4 is directed downward. The carrier member A is moved along the rod 1 50 until the pencil 4 comes into contact with the card 5. By loosening the screw 14, the means 3 is turned so as to bring the axis of the roller 16 in a vertical position.

As illustrated in Fig. 4, the roller 16 is 55 drawn over the skin surface from one side of the face around to the other. In this case the carrier member A will pivot about the rod 1 and when the roller 16 is on the right side of the person's face, the pencil 4 will be 60 in the region R on the card. When the roller is on the left side of the person's face, the pencil will be in the region L on the card.

For purposes of comparison the card is cut along the line obtained; and the cut edge is 65 brought against the face, or additional lines

may be produced for comparison with ones previously drawn. It is readily seen that in obtaining a horizontal profile or a vertical profile, the line produced on the card will show irregularities corresponding to the irregularities in the profile and such a line may be used as a basis for comparison. 70

In certain cases where it is desirable to obtain measurements, a scale may be printed on the card 5, or the tablet 6 may be marked 75 with a scale. If the distance between any two points is desired and when it is not necessary to obtain a complete outline, the points may be indicated on the card. In this instance, it is preferable to substitute the pointed 80 means shown in Fig. 3a for the means 3 shown in Fig. 1.

As previously suggested the present invention is particularly useful in the dental profession although other uses may suggest themselves. A permanent record of profiles may be kept and may be useful for identification purposes. In orthodontia, profiles may be recorded at various times during the treatment of a patient to show what progress has 85 been made and also to aid in determining the steps to be taken at the different stages towards obtaining a more pleasing profile. 90

What we claim is—

1. Apparatus comprising a rod, means for supporting the rod in a substantially vertical position adjacent the human face, a carrier member mounted on and movable along the said rod and also movable toward or away from the face, means extending from the said carrier member the end of which latter means is adapted to be drawn horizontally or vertically across the skin surface, a tablet mounted on the means for supporting the said rod, means for maintaining the said tablet in adjusted horizontal or vertical position, and a marking means adjustably mounted on the said carrier member whereby the said marking means may be brought into contact with the said tablet when the latter is in a horizontal or vertical position. 100

2. Apparatus comprising a guide member, means for supporting the said guide member adjacent the human face, a tablet adjustably mounted on the said supporting means adjacent the said guide member, means for maintaining the said tablet at any level in the region of the face, means for attaching a card to the said tablet, a carrier member mounted on the said guide member and adapted to be moved along the same and also toward and away from the face, means extending from the said carrier member the end of which means is adapted to be drawn across the skin surface at any level from one side of the face to the other, and a stylus mounted on the said carrier member and adapted to be brought into contact with the said card. 115

3. Apparatus comprising a rod, a sleeve movable along the said rod, a second rod con- 120

130

nected to the said sleeve on the said first rod, a rotatable sleeve on the said second rod, set screws for the said sleeves, a tablet attached to the said rotatable sleeve, a third rod par-
5 allel to the said first rod, a block movable along and rotatable on the said third rod, a reciprocating means mounted on the said block, a tracing implement extending from one end of the said reciprocating means, a
10 stylus adjustably mounted on the other end of the said reciprocating means, and adapted to engage the said tablet and a common sup-
port for the said first and third rods.

In testimony whereof, I have hereunto sub-
15 scribed my name this 8th day of January,
1930.

JAMES A. MALCOLM.

In testimony whereof, I have hereunto sub-
20 scribed my name this 8th day of January,
1930.

THOMAS W. WOOTTON.
